United States Patent Office.

JOHN ROGERS, OF NEW YORK, N. Y.

Design No. 4,287, dated August 9, 1870.

DESIGN FOR A GROUP OF STATUARY.

The Schedule referred to in these Letters Patent and making part of the same.

To all whom it may concern:

Be it known that I, JOHN ROGERS, of the city, county, and State of New York, have invented or produced a new and original Design for a Group of Statuary, and I do declare that the following is a full and exact description of the same.

The title of the group is: "Coming to the Parson."

The parson is represented as sitting in his easy chair before a table, reading a newspaper, and is just looking up to notice a young man and woman approaching him on his right, hand-in-hand.

The young woman is bashfully biting the corner of her shawl, while her lover points to her with his right thumb, and signifies to the parson that they want to be married.

The young man's dog is seen coming between his legs and worrying the parson's cat.

All of which is shown in the accompanying drawing.

Having thus described my invention,

What I claim, and desire to secure by Letters Patent, is—

The design for a group of statuary, as herein shown and described.

M. COLWELL,

JAMES M. HART.
